UNITED STATES PATENT OFFICE.

JOSEPH H. MILLS, OF RICHMOND, INDIANA.

PLASTIC COMPOSITION.

1,088,164.

Specification of Letters Patent.

Patented Feb. 24, 1914.

No Drawing.

Application filed July 19, 1909. Serial No. 508,286.

To all whom it may concern:

Be it known that I, JOSEPH H. MILLS, a citizen of the United States, residing at Richmond, Wayne county, Indiana, have invented a certain new and useful Plastic Composition, of which the following is a specification.

My invention relates to a new and useful plastic composition designed for various 10 uses, particularly in the ornamenting and embellishing of objects or surfaces as an economical and efficient substitute for wooden carvings and the like.

The principal advantage of my new composition resides not only in its plastic character and its consequent capability of being given the proper form or ornamentation by means of dies or the like, but also its ability 15 to retain its plastic or semi-rigid character 20 in order that it may be shaped by hand or otherwise to the surface or contour of the object to which it is to be applied.

My new plastic composition possesses other 25 advantageous properties among which may be named its tough and elastic character maintained under all conditions and for any length of time, with the result that it is enabled to adapt or conform itself to the expansions and contractions or shrinkages of 30 the object to which it is applied, and also permit nails or the like to be driven therethrough without fracturing or cracking the same.

While my plastic composition has been 35 more particularly designed for use by me for the purpose of ornamenting and embellishing caskets, yet it will be understood that my invention is not limited to such particular character of use but that I contemplate 40 using such composition wherever applicable.

Speaking in general terms, my composition comprises essentially resinous matter, a drying vegetable oil and a mineral filler or a fibrous matter or both.

Referring to the plastic composition as compounded by me, I employ resinous matter such as ordinary rosin, a drying vegetable oil such as boiled linseed oil and a mineral filler such as whiting and in respect 45 to the fibrous matter the same should be in a reduced or finely divided condition which is answered by sawdust. I prefer to mix and combine these ingredients in the following proportions by weight: rosin, twelve parts, 50 linseed oil, one part and whiting thirty parts. In the event that fibrous matter is to be em-

ployed, instead of the mineral filler, I prefer to mix and combine the ingredients in the following proportions by weight: rosin twelve parts, linseed oil one part and sawdust five parts. 60

It will be understood that the proportions above given may be varied between certain elements according to the particular use of the composition or place of application or the particular degree of plastic character required, but it will be found that the proportions of the ingredients here given as the preferred ones will be found suitable and proper for most uses. The resulting composition is plastic in character and may be bent or twisted by hand so as to conform it to the surface of the object or article to which it is to be applied, the composition remaining in this plastic or semi-rigid condition and not hardening or becoming brittle after a lapse of time or after exposure but nevertheless retaining a permanent set as to the ornamentation or configuration given it by dies or otherwise. 70

Referring to the use of the composition in the ornamentation of burial caskets and speaking of the practice employed in this connection, without intending to limit myself to such particular use, the composition 85 may be employed or attached to the shell of the casket either directly or indirectly and in any suitable manner. When the composition is attached directly to the shell I permit to preliminarily cover the same with the usual cloth which is to form the covering of the casket the cloth being laid over the composition and a die thereupon pressing the cloth directly into the surface of the composition. Owing to the adhesive character 90

95 of the composition and by reason of the forcing of the nap of the cloth by the pressure of the die into the surface of such composition, the cloth will be securely affixed to the composition and moreover partake of the same 100 ornamental design as is impressed on the composition itself. The cloth, with the composition or series thereof on its inner side, is now glued or otherwise secured to the shell. Also if desired the composition products may be directly secured to the shell of the casket in suitable manner as by gluing or nailing or tacking, preferably by gluing, and the same may be subsequently covered 105 with the cloth. The elastic property of my composition permits this covering of the product by means of the die, the composition 110

yielding and permitting the cloth to be pressed into it without any tearing or rupturing of such cloth. The articles thus employed or formed are both elastic and plastic in character and retain their original shape but are at all times capable of being bent or shaped to conform to the article or object to which it is to be applied.

For the purpose of a clear understanding of the advantageous properties of my plastic composition I have thus chosen to describe it in connection with one of its commercial

uses but it will be understood that the same may be employed in a great variety of situations owing to the advantageous properties 15 which it possesses.

I claim:

A plastic composition consisting of resin twelve parts, linseed oil one part and sawdust five parts.

JOSEPH H. MILLS.
